US00D510100S

(12) **United States Design Patent** (10) Patent No.: US D510,100 S
Schneider et al. (45) Date of Patent: ** Sep. 27, 2005

(54) TYPE FONT

(75) Inventors: **Werner Schneider**, Bad Laasphe (DE);
Helmut Ness, Kelkheim (DE)

(73) Assignee: **Heidelberger Druckmaschinen AG,**
Heidelberg (DE)

(**) Term: 14 Years

(21) Appl. No.: 29/175,112

(22) Filed: **Jan. 30, 2003**

(30) **Foreign Application Priority Data**

Aug. 24, 2002 (DE) 4 02 50 014

(51) LOC (8) Cl. 18-03

(52) U.S. Cl. D18/24

(58) Field of Search ..... D18/24-33; 101/398.

(58) Field of Search D16/24 55, 101/398,
